UNITED STATES PATENT OFFICE.

FRANCESCO BISESI, OF NEW YORK, N. Y.

KEY-OPERATED LOCK.

1,027,173.

Specification of Letters Patent. Patented May 21, 1912.

Application filed October 3, 1911. Serial No. 652,503.

To all whom it may concern:

Be it known that I, FRANCESCO BISESI, a subject of the King of Italy, and a resident of the city of New York, borough of Manhattan, in the county and State of New York, have invented a new and Improved Key-Operated Lock, of which the following is a full, clear, and exact description.

Among the principal objects which the present invention has in view are: to provide a lock of the character mentioned with a plurality of bolts to augment the strength of the fastening; to provide in a lock of the character described a plurality of keys operable successively upon a lock bolt which keys when used in reversed order retract the bolt previously protruded; to provide a lock of the character mentioned with a safety or secret latch to lock the bolt in full extended position to require the release of the latch prior to retracting said bolt; and to provide a lock operable by a plurality of keys the use of each successive key placing the lock in position to prevent the use of a preceding key.

One embodiment of the present invention is disclosed in the structure illustrated in the accompanying drawings, in which like characters of reference denote corresponding parts in all the views, and in which—

Figure 1 is a side view of a lock constructed and arranged in accordance with the present invention, the cover plate of the lock being removed; Fig. 2 is a similar view 35 of the guard plate shown in Fig. 1 being removed to show one set of tumblers and the service key employed in conjunction with the present lock; Fig. 3 is a cross section taken on the line 3—3 in Fig. 1; Fig. 4 is a section taken on the line 4—4 in Fig. 2; Figs. 5 and 6 are side views of fragments of the lock constructed in accordance with the present invention, showing the disposition of the tumblers and service bolt of the lock prior to and after being shot by the operation of the service key; Fig. 7 is a view similar to Fig. 2 showing the service and auxiliary bolts after being shot to full locked position by the operation of the master key; Fig. 8 is a side view of a fragment of the lock, showing the bolt locking latch with which the present lock is provided; Fig. 9 is a cross section of a fragment of the lock the section being taken on the line 9—9 55 in Fig. 8, showing in conjunction therewith

the master key of the lock; Fig. 10 is a side view of the service key employed in conjunction with the lock herein described; and Fig. 11 is a side view of the master key employed in conjunction with the lock herein described.

As seen in the accompanying drawings, the lock is provided with a plurality of bolts, which for the convenience of description I have designated as the service bolt 16 and the auxiliary bolts 17, 17. The auxiliary bolts 17, 17, under certain conditions of the service bolt 16, are operated thereby to project or retract the same. For this purpose the service bolt 16 is provided with a tail piece 18, from the side whereof are extended the lugs 19, 19 and the shoulders 20, 20. Between the lugs 19 and shoulders 20 are extended the ends of the arms 21, 21, which arms are extended from and rigidly secured to the guide rods 22 of the said auxiliary bolts. To support the auxiliary bolts in their reciprocated action the striker plate 23 is perforated for the passage therethrough of each of the bolts 17. The rods 22 are extended between the arms of a guide plate 24. Each of the plates 24 takes the thrust of a spiral spring 25 which is wound about each of the rods 22. The springs 25 normally operate to retract the bolts 17 when so permitted by the movement of the service bolt 16.

Normally the springs 25 are extended to their full limit, as shown in Figs. 1 and 2 of the drawings, where, as therein shown, the ends of the auxiliary bolts 17 are flush with the striker plate 23. In this position the inner ends of the bolts 17 rest the one on the plate 24 and the other against the side of the structural bolt 26.

The service bolt 16 is operated by the service key 27 to be extended; as shown in Fig. 6 of the drawings. In the full extended position to which the service key 27 may move the said bolt, the lugs 19 rest in juxtaposed relation to but do not bear upon the arms 21. It will be understood that the normal operation of the service bolt 16 is within the limits between the back plate of the casing 28 and the normal position of the arms 21. It is when the service bolt 16 is moved by the master key 29 to the extreme forward position, as shown in Fig. 7, that the lugs 19 serve to press on the arms 21 to move the auxiliary bolts 17 to the full locked position,

as seen in Fig. 7 of the drawings. Under other conditions the springs 25 operate to maintain the bolts 17 retracted with the forward ends thereof flush with the striker plate 23.

The bolt 16 is held in its operative position by a dog 30, mounted rigidly on the said bolt and extended from the side thereof, which dog 30 is successively engaged by the 10 pivoted tumbler plates 31. Each of the plates 31 is provided with a longitudinal slot 32 having extended therefrom offsets of recesses 33 and 34. The plates 31 engage the dog 30 by the latter passing into the recesses 33 and 34, the sides whereof impinge upon the said dog and prevent the retraction of the bolt 16.

The tumbler plates 31 are pivotally mounted on the post 35, which is fixed upon 20 the side of the casing 28 and further serves as a guide for the bolt 16, a slot 36 being formed in the tail piece 18 to receive the said post. The tumbler plates 31 are depressed by the springs 37 which anchor in a housing 25 38 of any suitable construction.

It will be understood that when the bolt 16 is locked in the extreme forward position the recesses 34 of the tumbler plates 31 engage the dog 30. By the operation of the 30 service key 27 the plates 31 may be lifted, in which position the springs 25 would retract the bolts 16 and 17, thus defeating the purpose for which the present lock is intended. It is designed that when the service bolt 16 and the auxiliary bolts 17, 17 are 35 fully extended, as shown in Fig. 7 of the drawings, the recesses 39 formed in the tumbler plates 40 will hold the dog 30 to maintain the bolts in the locked position irrespective of the movement of the plates 31. The master key 29 is provided with a 40 set of wards the duplicates of the wards in the service key, and this to enable the master key to lift the tumbler plates 31 and 40 simultaneously, thereby freeing the dog 30 from engagement with both the recesses 34 in the plates 31 and the recesses 39 in the plates 40.

The plates 31 and 40 are divided by the 50 partition 41 in which is formed a longitudinal slot for the movement of the dog 30 and the key opening 42 for the passage of the master key 29.

To accommodate the service key 27 the bolt 55 16 is provided with the shoulders 43, spaced apart to be moved successively into the forward and rearward path of the ward of the key 27, to be engaged thereby to advance the bolt 16 to the position shown in Fig. 6, 60 and to retract the same to the position shown in Fig. 2, the said ward of the key 27 passing out of engagement of each of the said shoulders at the extreme of its forward or rearward movement. When the key 27 has 65 disposed the bolt in the position shown

in Fig. 6 of the drawings the shoulders 44 have been moved into position to be engaged by the ward of the master key 29 when the same is now inserted in the lock. The dog 30 has been moved forward to the position shown in Fig. 6 where it rests in the recess 33 preventing the retraction or advance of the bolt 16 except as the tumbler plates 31 be lifted. The inner shoulder of the projection 45 formed on the plates 40 also serves to block the further projection of the bolt 16 and dog 30 unless the said plates 40 be lifted. It is the master key 29 only which possesses the wards capable of lifting both sets of plates 31 and 40, therefore the key 27, 80 though it engage the shoulders 44 of the bolt 16, may not move the bolt 16 to the full locked position shown in Fig. 7. The key 29 is relied upon to shoot the bolts 16 and 17 to the full locked position shown in Fig. 85 7, and to retract the same from the position shown to the position shown there in Fig. 6. From the position shown in Fig. 6 the key 27 is relied upon to retract the service bolt 16.

Thus, it will be seen that the lock is variously operated by two separately shaped keys, one of the said keys operating the lock for what are here termed service conditions and the other for a permanent closure. The employment of separate keys 90 renders it possible, if the custodian have the so-called master key, to place the lock in position to prevent the release by the custodian of the service key, while the service key is utilized for ordinary securement of the 95 lock.

It is to prevent the picking of the lock by the usual method of obtaining an impression of the tumblers and from such impression manufacturing a suitable key to 105 operate the lock, that I have provided the latch bar 46. The latch bar 46 is provided with a spring section 47 and is secured by the rivet 48 to a cover plate 49. The plate 49 holds in operative position the plates 40. In the said plate a slot 50 is formed lengthwise of which the dog 30 travels as the bolt 16 is manipulated. At the far end of the slot 50 the dog 30 passes under the bar 46, the spring section 47 yielding to permit the lift of the said bar as the dog passes thereunder to seat the said bar at the rear of said dog to prevent the return thereof. In the above described position it is obvious 115 that the bolt 16 to which the dog 30 is rigidly attached may not be retracted until the bar 46 is removed from engagement with the dog 30. For this purpose the bar 46 is provided with an arm 51, upon the end whereof is mounted a pin 52. The pin 52 120 is centrally disposed in a guide tube 53 which is likewise rigidly secured on the arm 51. The tube 53 forms an interior guide for the key 29, fitting as it does the tubular end 54 of the said key. The pin 52 is disposed 125 130

in the path of a plunger pin 55, the end whereof rests upon the pin 52 when the key 29 is properly adjusted upon the tube 53. The outer end of the plunger pin 55 is furnished with a button 56 with which to operate the plunger pin. The said plunger pin 55 is held outwardly extended by a spiral spring 57 wrapped about the said plunger pin and disposed within the hollow 10 of the key 29, as shown best in Fig. 9 of the drawings.

When the key 29, having the plunger pin 55 mounted therein, is inserted in the key-hole 58 and passed through the opening 42, 15 the operation is as follows: The key is turned to the position shown in Fig. 9 of the drawings, the wards 59 and 60 lifting the tumblers 31 and 40 respectively to remove the recesses 33, 34 and 39 from engagement 20 with the dog 30. The operator now presses upon the button 56 which removes the bar 46 from the path of the dog 30 and permits the springs 25, 25 to retract the bolts 17, 17 and 16 to the service position of the 25 bolt 16, as shown in Fig. 6 of the drawings. The key 29 is then revolved and withdrawn. It will be observed, however, that the bolt 16 is not retracted and that the closure member upon which the lock is mounted is not free. 30 It requires the further operation of the service key 27, which is now inserted to engage one of the shoulders 43, to move the bolt 16 to the full released position shown in Fig. 2 of the drawings.

35 While I have herein detailed the construction and arrangement of the various parts shown in the accompanying drawings as disclosing the embodiment of the invention, I do not wish to be limited to the particular 40 construction and arrangement of the said instrumentalities, as these may be varied without affecting the invention.

Having thus described my invention, what I claim as new and desire to secure by Letters Patent is:—

1. In a lock of the character described, a bolt to progressively assume successive locking positions; a plurality of engaging tumblers for said bolt to hold the said bolt in each of its assumed positions; and a plurality of keys to move said bolt each of said keys having wards to release one of said tumblers from holding relation to said bolt, and one of said keys provided with wards to engage all of said tumblers to move the same in position to release said bolt.

2. In a lock of the character described, a bolt to progressively assume successive locking positions; a plurality of engaging tumblers for said bolt to hold the said bolt in each of its assumed positions; a plurality of keys to move said bolt, each of said keys having wards to release one of said tumblers from holding relation to said bolt, and one 65 of said keys provided with wards to engage

all of said tumblers to move the same in position to release said bolt; and a spring actuated latch independent of said tumblers to lock said bolt in one of said positions.

3. In a lock of the character described, a bolt to progressively assume successive locking positions; a plurality of engaging tumblers for said bolt to hold the said bolt in each of its assumed positions; a plurality of keys to move said bolt, each of said keys having wards to release one of said tumblers from holding relation to said bolt, and one of said keys provided with wards to engage all of said tumblers to move the same in position to release said bolt; a spring actuated latch independent of said tumblers to lock said bolt in one of said positions; and means carried by said key having the wards for all of said tumblers for releasing said latch.

4. In a lock of the character described, a bolt to progressively assume successive locking positions; a plurality of engaging tumblers for said bolt to hold the said bolt in each of its assumed positions; a plurality of keys to move said bolt, each of said keys having wards to release one of said tumblers from holding relation to said bolt, and one of said keys provided with wards to engage all of said tumblers to move the same in position to release said bolt; a spring actuated latch independent of said tumblers to lock said bolt in one of said positions; and a plunger pin reciprocatively mounted in the key having wards to release all of said tumblers, said pin arranged to release said latch when said key is in operative position in said lock.

5. A lock such as described, having a service bolt; a plurality of tumblers to hold said bolt in extended position; and a plurality of keys, each having wards, a portion of the wards of one of said keys being duplicates of all the wards on the other of said keys.

6. A lock such as described, having a service bolt; two sets of tumblers to hold the bolt in two extended positions, one of said sets being adapted to hold the bolt in both of said positions, and the other of said sets to hold the bolt in one only of said positions; and a plurality of keys adapted to engage the said bolts to move the same; one of said keys having wards to engage the set of tumblers which hold the bolt in the two positions, the other of said keys having wards the duplicate of the wards on the other of said keys; and an extra set of wards to engage the said tumblers which hold the bolt in full extended positions.

7. A lock such as described, having a bolt; a plurality of tumblers to hold said bolt in two variously-extended positions, one set of said tumblers being arranged to hold the bolt in the greatest extended position only;

an auxiliary latch to engage the bolt in the fullest-extended position only; a key having two sets of wards variously arranged to engage both sets of said tumblers, to release said bolt; means carried by said key for releasing said auxiliary latch from engagement from said bolt; and a second key, having wards to engage the said set of tumblers adapted to hold the bolt in both positions,

said wards being duplicates of one set of 10 wards on the other of said keys.

In testimony whereof I have signed my name to this specification in the presence of two subscribing witnesses.

FRANCESCO BISESI.
